UNITED STATES PATENT OFFICE.

MORRIS BERMAN, OF BROOKLYN, NEW YORK, ASSIGNEE TO RELIANCE METAL SPINNING & STAMPING COMPANY, OF BROOKLYN, NEW YORK, A CORPORATION OF NEW YORK.

SOCKET COVER.

Application filed June 16, 1921. Serial No. 477,891.

To all whom it may concern:

Be it known that I, MORRIS BERMAN, a citizen of the United States, and a resident of the city of New York, borough of Brooklyn, county of Kings, and State of New York, have invented certain new and useful Improvements in Socket Covers, of which the following is a full, clear, and exact description.

10 The present invention relates to socket covers for electric light fixtures, and it has for its object to provide a socket cover so constructed that it may be adapted for use either with a ball or spherical lamp, or with 15 a pear-shaped lamp and shade as desired, without the necessity of dismantling and disconnecting the socket cover from the rest of the fixture.

A further object of the invention is to provide 20 a socket cover in which the cover plate is connected to the body portion by a detachable joint which shall be invisible when the apparatus is in use, and while readily detachable, forms an effective union between 25 the body portion and the cover plate.

To the above ends, the present invention consists of a socket cover comprising a body portion and a cover plate with a detachable connection between the body portion and 30 the cover plate, and further consists of the socket cover which will be hereinafter described and claimed.

The invention is illustrated in the accompanying drawing, in which—

35 Figure 1 shows a vertical diametrical sectional view through a socket cover embodying the invention, adapted for use with a ball or spherical lamp, the lamp and socket cover being shown in elevation.

40 Figure 2 shows a top plan view of Figure 1.

Figure 3 shows a view looking at the lower edge of the body portion with the cover plate removed.

45 Figure 4 shows a fragmentary sectional view somewhat enlarged as compared with the remaining figures, illustrating the construction of the joint between the body portion and cover plate.

50 Figure 5 shows a view similar to Figure 1 with a cover plate adapted to support a shade, which is also shown in section and with the socket cover and pear-shaped lamp shown in elevation.

Similar reference characters will be employed to designate corresponding parts.

In the drawing, the socket cover is shown as comprising a body portion 1 which is of the usual and well-known ball shape outwardly flaring at its lower end as shown at 60 2, and provided with a peripheral flange 3 surrounding the lower open end. At its upper end the body portion 1 is provided with an opening 4 through which passes the conductor or support 5, and the body portion 65 1 is held in position and supports the socket 6 by any suitable means as by means of the nut 7. The lower open end of the body portion 1 is closed by the cover plate 8, which is ornamented in any desirable manner well known in this art, and in the form shown in Figure 1, it is provided with a central opening 9 exposing the end of the socket 6 so that a ball or spherical lamp 10 may be connected to the socket 6 and be exposed upon 70 the under side of the cover plate 8. It is sometimes required to change the cover plate 8 so that one having a desired ornamental surface may be substituted for another, or as shown in Figure 5, so that a cover plate 80 adapted for use with a pear-shaped lamp and having means such as the projecting flange or collar 11, having set screws 12, may be substituted to support a shade 13 about the pear-shaped lamp 14. For this 75 purpose I have provided a detachable connection or joint between the body portion 1 and the cover plate 8. This joint comprises a relatively narrow inturned flange 15 carried by the outer edge of the cover plate 8, 80 which flange will preferably be disposed at an angle coinciding with and forming a continuation of the flaring surface 2 of the body portion 1, and it is provided with a notch 16, which notch is formed entirely 85 within the inturned flange 15. The flange 3 on the lower edge of the body portion 1 is preferably a vertical flange, and it is provided with a plurality of projections 17. The outer circumference of the flange 3 will 90 be of such diameter as will fit the opening formed by the inner peripheral edge of the flange 15 of the cover plate, but the projections 17 will extend beyond the outer surface of the flange 3 so that they may be positioned beneath the inturned flange 15 of the cover plate as shown in Figures 1, 2, 4 and 5 of the drawing, and yet readily pass

out or in through the notch 16 in the flange 15. This arrangement is such that by bringing the projections 17 successively in register with the notch 16, the cover plate and body portion may be connected together by turning one with relation to the other so as to position the projections 17 out of register with the notches 16, as shown in Figure 2 of the drawing.

10 It will be noted that when the parts are coupled together, the overturned flange 15 will be uppermost when the socket covers are pendent as they usually are, and thus will be concealed or substantially invisible, and that furthermore the joint, because of the fact that the flange 15 coincides with the outwardly flaring bell portion 2, has the appearance of the usual flanged or overlapping seamed joint employed in connecting 15 pressed sheet metal parts together.

15 It will be apparent also that the cover plate may be at all times readily removed and replaced by another when desired and that instead of a cover plate adapted for 20 use with a ball or spherical lamp being substituted, a cover plate such as shown in Figure 25

5 may be employed, and this may be accomplished without the necessity of removing the connection of the socket cover to the fixture.

Having described my invention, I claim:

1. A socket cover comprising a body portion and a cover plate, an inwardly-extending flange on said cover plate arranged to receive the lower end of the body portion, and a detachable connection between the lower end of the body portion and the flange of the cover plate. 30

2. A socket cover comprising a body portion and a cover plate, the cover plate having an inwardly extending notched flange and the body portion having projections arranged to engage with the notched flange of the cover plate. 35

3. A socket cover comprising a body portion and a cover plate, said cover plate provided with an inwardly extending notched flange and the body portion having a flange provided with projections, the flange on the cover plate embracing the flange on the body portion. 40 45

MORRIS BERMAN. 50
